UNITED STATES PATENT OFFICE.

MEINICH SKAU, OF CHICAGO, ILLINOIS, ASSIGNOR TO ACME APPLIANCE COMPANY, OF CHICAGO, ILLINOIS, A CORPORATION OF ILLINOIS.

INK-ROLLER.

1,287,121.

Specification of Letters Patent. Patented Dec. 10, 1918.

Application filed March 6, 1917. Serial No. 152,610.

To all whom it may concern:

Be it known that I, MEINICH SKAU, a subject of the King of Norway, residing at Chicago, in the county of Cook and State of Illinois, have invented a certain new and useful Improvement in Ink-Rollers, of which the following is a specification.

My invention relates to an improved form of ink roller by which a fabric is mounted upon a supporting roller, which roller is preferably constructed to engage and retain the edges of the fabric in place. The fabric preferably is a "pile" fabric, that is, a fabric having a woven body portion with outstanding threads woven into the body portion and projecting outward therefrom at substantially right angles to said body portion. An ink roller thus constructed may be used for many purposes where it is required to ink type for different purposes, and by constructing the supporting portion of the roller to clamp and hold the fabric in place a substantially uniform inking surface is secured over the joint in the fabric and by using a pile fabric the woven body portion of the fabric contains a considerable quantity of ink which is fed by capillary action into the projecting threads or pile and communicated by them to the type to be inked.

My invention will best be understood by reference to the accompanying drawings showing preferred embodiments of my invention, which are as follows:

Figure 1 shows in longitudinal sectional view, my improved ink roller mounted upon a tubular support.

Fig. 2 is an end view of the roller shown in Fig. 1.

Fig. 3 is an enlarged sectional view through a form of pile fabric I prefer to use in making my ink roller.

Fig. 4 shows in sectional view one end of a roller similar to that shown in Fig. 1, provided with an end bearing.

Fig. 5 shows in a view similar to Fig. 1 an ink roller in which the fabric is mounted upon a wood roller, and

Fig. 6 is an end view of the roller shown in Fig. 5.

Similar numerals refer to similar parts throughout the several views.

The ink roller shown in Figs. 1 and 2 consists of a tubular body portion 10 split longi-

tudinally along one side, which body portion is surrounded by a strip 11 of fabric, the edges of which are forced through the split end in the tube, as indicated at 12, the fabric being held in position partly by the spring of the tube and partly by adhesive material such as glue or shellac applied to the inturned edges. 60 The fabric is preferably of the kind shown in Fig. 3, consisting of a body portion 13 and a pile 14 woven into the body portion and having outstanding ends substantially in the same surface. I find the best results 65 are secured by using a wool fabric in which the pile is formed of a large number of threads, so that the pile is relatively firm and in this way affords a yielding and effective surface for engaging the type to communicate the ink thereto.

In the construction shown in Fig. 4 the end of the tube 10 is provided with a cap 15, the flange of which encircles the tube and is a close fit thereon, so that it may be held in 75 place by frictional engagement with the tube, this cap being provided with a central aperture 16 for receiving the bearing rod of the roller.

In the construction shown in Figs. 5 and 6 a wooden roller 17 is employed and the fabric 11^a is held in place on the surface of the roller by adhesive such as glue or shellac, and in addition the edges of the fabric may be secured to the roller 17 by small 85 tacks or nails 18. The roller 17 may, if desired, be provided with bearing rods 19.

I find that an ink roller constructed as described is superior to rollers heretofore made for this purpose of solid felt or built up of 90 felt washers, for the reason that felt of sufficient firmness to give good results, absorbs but a small quantity of ink and must, therefore, be frequently reinked in order to satisfactorily perform its intended function. 95 With my construction, on the other hand, the woven fabric holds a large quantity of ink which, by the action of the roller upon the type, is practically all available for inking the type with the result that one filling 100 of ink lasts for a relatively long time. I also find that an ink roller constructed as above described is superior to an ink pad of any material for the reason that the type in passing over the roller do not rub upon 105 the surface of the roller, since the latter

rotates, whereas with an ink pad the rubbing of the type on the pad, where the latter is made of fabric, tends to pull out the threads of the fabric, thus materially reducing its life.

In connection with my improved ink roller and particularly in connection with the roller covered with pile fabric, I find it of advantage to employ a trough 20 around

- 10 the lower portion of the roller to contain the ink with which the roller is used. The pile of the fabric is preferably so related to the trough as to nearly or quite engage the inner surface of the trough, as a result of which, as the roller rotates in the trough the pile of the fabric, passing through the ink, stirs up the same so as to keep the heavier sediment of the ink in suspension and thus maintain a uniform condition of ink applied to the type. Where this combination is not employed there is a tendency on the part of the ink to separate, the heavier solid portion of the ink tending to remain in the body portion of the fabric and in the bottom 25 of the trough while the lighter fluid portion of the ink is communicated by the inking surface of the roller to the type, thus frequently giving too light an ink impression.

It will be understood that I do not limit myself in carrying out my invention to the particular kind of fabric shown and described, although I find such fabric to give excellent results, nor do I limit myself to the exact construction shown and described, 35 as I may employ equivalents thereof without departing from the scope of the appended claims.

What I claim is:

1. In an ink roller, the combination of a 40 tube split longitudinally along one side, a strip of pile fabric surrounding the tube and having its edges between the longitudi-

nal edges of the tube, and adhesive material on the inturned edges of the fabric.

2. In an ink roller, the combination of a 45 tube split longitudinally along one side, a strip of fabric surrounding the tube and having its edges between the longitudinal edges of the tube, and adhesive material on the inturned edges of the fabric. 50

3. In an ink roller, the combination of a tube split longitudinally along one side, and a strip of pile fabric surrounding the tube and having its edges between the longitudinal edges of the tube, said tube being of 55 spring material and holding the fabric between the edges thereof by the clamping action of said tube.

4. In an ink roller, the combination of a tube split longitudinally along one side, and 60 a strip of fabric surrounding the tube and having its edges between the longitudinal edges of the tube, said tube being of spring material and holding the fabric between the edges thereof by the clamping action of said 65 tube.

5. In an ink roller, the combination of a tube split longitudinally along one side, a strip of pile fabric surrounding the tube and 70 having its edges between the longitudinal edges of the tube, adhesive material on the inturned edges of the fabric, and end bearings for the tube comprising end caps encircling the ends of said tube.

6. In an ink roller, the combination of a 75 tube split longitudinally along one side, a strip of fabric surrounding the tube and having its edges between the longitudinal edges of the tube, and end bearings for the tube comprising end caps encircling the ends 80 of said tube.

In witness whereof, I hereunto subscribe my name this 1st day of March, A. D. 1917.

MEINICH SKAU.
